UNITED STATES PATENT OFFICE.

SAMUEL RICHARD AND FRED GLUCK, OF EAST PITTSBURG, PENNSYLVANIA.

ADVERTISING DEVICE.

No. 918,369.

Specification of Letters Patent. Patented April 13, 1909.

Application filed September 16, 1907. Serial No. 393,097.

To all whom it may concern:

Be it known that we, SAMUEL RICHARD and FRED GLUCK, citizens of the United States of America, residing at East Pittsburg, in the county of Allegheny and State of Pennsylvania, have invented certain new and useful Improvements in Advertising Devices, of which the following is a specification, reference being had therein to the accompanying drawing.

This invention relates to advertising devices, of that type designed for displaying business cards, announcement cards, and similar notices in hotels and public places. The device may be even constructed upon a very large scale for displaying sign boards upon public thoroughfares.

Our invention aims to provide a novel device for intermittently displaying signs, the device being electrically operated and the illumination of the signs automatically controlled.

We further aim to provide a device which will be positive in its action, free from all danger of injury by ordinary use, thoroughly protected from the forces of nature when used as an outside advertising medium, and last but not least, a structure that is simple and durable and easily accessible.

The invention will be presently described in detail and then specifically pointed out in the appended claims, and reference will now be had to the drawings wherein,

Figure 1 is a longitudinal sectional view of our device, illustrating the mechanism thereof in front elevation and with the circuit making and breaking mechanism not shown, Fig. 2 is a cross sectional view of the device taken on the line $w-w$ of Fig. 1, looking in the direction of the arrow adjacent to said line, Fig. 3 is a horizontal sectional view of the device, partly in plan, also illustrating diagrammatically the electrical circuit of the motor used in connection with the device, Fig. 4 is a cross sectional view of the device, taken on the line $x-x$ of Fig. 1 looking in the direction of the arrow associated with said line, illustrating diagrammatically the electrical circuit and source of energy employed for illuminating the exposed signs of the device, Fig. 5 is a similar view taken on the line $y-y$ of Fig. 1 looking in the direction of the arrow contiguous

to said line, Fig. 6 is a front elevation of the device, partly broken away, Fig. 7 is a side elevation of the ratchet mechanism forming part of the device, Fig. 8 is a similar view of a portion of the ratchet mechanism, Fig. 9 is a rear elevation of the ratchet mechanism, Fig. 10 is a similar view of a portion of the same, Fig. 11 is a similar view of the trip constituting part of the ratchet mechanism, Fig. 12 is a front elevation of the ratchet mechanism and trip, and Fig. 13 is an elevation of a portion of the ratchet operated shaft.

To put our invention into practice, we construct the device of two end plates 1 and 2, these plates having their lower ends flanged, as at 3, whereby they can be secured upon a suitable base plate or support. The end plates 1 and 2 are connected together by a stirrup 4 upon which is supported a motor 5 of a conventional form, said motor being driven from a suitable source of electrical energy 6 (see Fig. 3), connecting with the brushes 7 of the motor by wires 8 and 9; the electrical circuit being controlled by a suitable switch 10. The armature shaft of the motor 5 is provided with a worm 11, meshing with a worm wheel 12 mounted upon a shaft 14, journaled in brackets 15 carried by the motor 5. The shaft 14 extends through the end plate 2 and is provided with a sprocket wheel 16, the object of which will presently appear.

Journaled in the end plates 1 and 2 is a shaft 17, and vertically aligned with said shaft are stub shafts 18, these stub shafts being carried by the lower part of the end plates 1 and 2, while the shaft 17 is journaled in the upper ends of said plates. Upon the shaft 17 are mounted hexagon-shaped heads 19, and upon the stub shafts 18 are journaled hexagon-shaped heads 20, constituting part of an intermittently moving display rack for signs. The heads 19 and 20 at the angle points thereof are provided with notches 21 for engaging longitudinally disposed connecting rods 22 employed for pivotally connecting the links 23 of two endless chains together. The chains are located in close proximity to the end plates 1 and 2 and soldered or otherwise secured to said links 23 are sign holding frames 24, said frames being disposed longitudinally of the device.

and provided with open ends 25, whereby the signs or cards can be easily placed in said frames. In order that easy access can be had to said frames to change or re-arrange 5 the signs at any desired time, we cut away the end plate 1 at its front edge, as at 26.

The end plate 2 is provided with revolvable idle sprocket wheels 27 for carrying a sprocket chain 28 in close proximity to the 10 reduced end 29 of the shaft 17. The sprocket chain 28 passes over the sprocket wheel 16 of the shaft 14 and as will be presently described, imparts an intermittent movement to the endless chains carrying the sign holding frames 24.

Upon the reduced end 29 of the shaft 17 is loosely mounted a trip comprising a plate 30 having a flanged edge 31, a slot 32 and an arm 33. The arm 33 extends through a segment-shaped slot 34 formed in the end plate 2 (see Fig. 4 of the drawings, wherein the heads 19 are shown in dotted lines to more clearly show the construction upon the inner side of the end plate 2.) The arm 33 is connected to a bar 35, upon the inner side of the end plate 2, said bar being connected to an insulated contact arm 36, pivotally connected as at 37, upon the inner side of the end plate 2. The insulated arm 36 carries 25 contact points 38 which are normally held in engagement with contacts 39 by a coil spring 40, this spring being connected to one end of the stirrup 4. The contacts 39 are carried by a piece of insulation 41 secured to the end 30 plate 2, and these contacts together with the contact points 38 control the illumination of the signs carried by the movable frames 24.

Loosely mounted upon the reduced end 29 of the shaft 17 is a ratchet mechanism embodying a yoke having depending arms 42, a pierced lug 43 for receiving the end 29 of the shaft 17, and a radially disposed arm 44 for a pivoted weighted pawl 45. One of the arms 42 is provided with a pin 46 for engaging in the slot 32 of the trip plate 30, while the opposite arm is provided with a depending flanged projection 47, the object of which will presently appear.

The reduced end 29 of the shaft 17 is provided with a square shank portion 48, for a ratchet wheel 49, said wheel being retained thereon by a nut 50, screwed upon the threaded portion 51 of the shaft 17. The ratchet wheel 49 is normally engaged by 55 the weighted pivoted pawl 45 carried by the ratchet yoke. The flanged edge 31 of the trip plate 30 and the flanged projection 47 of the yoke arm 42 extend downwardly upon the sides of the sprocket chain and are 60 adapted to be engaged by the pins 52, which make a sliding contact, first elevating the plate 30 and then elevating said plate and the yoke in unison.

Fitting over the end plates 1 and 2 and the 65 mechanism just described is a detachable

hood 53 having its front wall provided with an opening 54 covered by glass or similar transparent material. Through this opening signs carried by the frames are displayed.

The hood 53 above the opening 54 is provided with a longitudinally disposed reflector 55, in which is located a plurality of incandescent lamps 56, said lamps being in circuit with a suitable source of electrical 70 energy 56^a (see Fig. 4) and with the contacts 39. Incandescent lamps can be of any approved form, and we do not care to confine ourselves to the location of the source of electrical energy for these lamps or for 80 the motor 5.

The operation of the mechanism just described, is as follows:—When the motor 5 is placed in operation a rotary movement is imparted to the shaft 14, which in turn 85 moves the endless sprocket chain 28. As this chain moves the pins 52 are carried over a predetermined course, and as they lie in the path of the projection 47, and the flanged edge 31 of the plate 30, the pins 52 90 will contact with these elements once during each circuit or circumvention of the sprocket chain 28. When one of the pins 52 impinges the flanged edge 31 of the plate 30, said plate is moved upwardly and through 95 the medium of the arm 33, bar 35 and the pivoted insulated arm 36, the electrical circuit through the incandescent lamps 50 is broken, (see dotted lines Fig. 4) extinguishing the lamps while the frames 24 are being 100 shifted to display another sign through the opening 54. As the plate 30 is moved

slightly in advance of the ratchet mechanism, the other pin 52 will engage the projection 47, elevate the ratchet yoke carrying 105 the pivoted weighted pawl 45, and as this pawl normally engages the ratchet wheel 49, said wheel and the shaft 17 will be rotated a predetermined part of a revolution. The exact movement of the shaft 17 is governed by the number of teeth carried by the ratchet wheel 49 and by the stroke or movement of the ratchet yoke. The plate 30 and the ratchet yoke are gradually elevated by the pins 52 and when released by said pins, 115 the yoke and plate assume their normal position by gravity, the weighted pawl 45 receding over the ratchet wheel 49 to obtain a fresh grip upon the same. The coil spring 40 immediately returns the bar 35 and insulated arm 36 to their normal position, again establishing a circuit to the incandescent lamps 56 and illuminating the sign carried by the frame 24, which has been moved in front of the sight opening 54.

As the endless chains carry a plurality of sign holding frames, numerous signs can be displayed by the device, the exposure of each sign being determined by the length of the sprocket chain 28 and the number of pins 130

located upon said chain. It is desirable to actuate the ratchet mechanism at such intervals in order that each sign will be displayed a sufficient period of time to allow the said sign being read. The switch 10 for controlling the motor 5 and a switch 57 which we employ in connection with the lamps 56, are adapted to control the entire operation of the advertising device, it of course being understood that the incandescent lamps 56 are only used when the device is operated at night and is located in dark places where the signs cannot be readily read.

15 It is obvious that the capacity of the device for displaying signs depends entirely upon the size of the device, and we desire it to be understood that such variations and modifications of the invention can be resorted to, as are within the scope of the appended claims.

Having now described our invention what we claim as new, is:—

1. An advertising device comprising an upper and a lower shaft, supports therefor, revolute heads carried by the shaft, traveling chains movably supported by the heads whereby the heads upon one shaft are connected to the heads upon the other shaft, sign holding frames carried by said chains, said upper shaft having a reduced end, a trip device mounted upon said reduced end, a pawl and ratchet mechanism mounted upon said reduced end, a motor driven sprocket chain mounted upon one of said supports, means carried by said motor driven sprocket chain and engaging said device mechanism for intermittently shifting them, a hood inclosing said supports and having a sight opening, electrical lamps adjacent to said opening, circuit wire connections between said lamps and a source of electrical energy, and means actuated by said device for controlling the electrical circuit.

45 2. An advertising device comprising an upper and a lower shaft, supports therefor, revolute heads carried by the shafts, traveling chains movably supported by and connecting said heads together, sign holding frames carried by said chains, said upper shaft having a reduced end, a ratchet wheel on said reduced end, a yoke mounted upon said reduced end, a counter-balanced pawl carried by said yoke and engaging the said ratchet and adapted when the yoke is actuated to actuate said ratchet and its shaft, a motor driven sprocket chain, mounted upon one of said supports, means carried by the motor driven sprocket chain and engaging said yoke for intermittently shifting it, and a hood inclosing said supports and having a side opening.

3. An advertising device comprising an upper and a lower shaft, supports therefor,

revolute heads carried by the shafts, traveling chains movably supported by and connecting said heads together, sign holding frames carried by said chains, said upper shaft having a reduced end, a ratchet wheel on said reduced end, a yoke mounted upon said reduced end, a counter-balanced pawl carried by said yoke and engaging the said ratchet and adapted when the yoke is actuated to actuate said ratchet and its shaft, a motor driven sprocket chain mounted upon one of said supports, means carried by the motor driven sprocket chain and engaging said yoke for intermittently shifting it, a hood inclosing said supports and having a sight opening, electrical lamps adjacent to said opening, circuit wire connections between said lamps and a source of electrical energy, means for controlling the circuit, an intermittently operated trip device mounted on said reduced end and adapted to actuate said controlling means, and means carried by the motor driven sprocket chain for intermittently operating said trip device.

4. An advertising device comprising an upper and a lower shaft, supports therefor, revolute heads carried by the shafts, traveling chains connecting the heads of one shaft to the heads of the other shaft, sign holding frames carried by said chains, said upper shaft having a projected end, a pawl and ratchet mechanism mounted upon said projected end of said shaft and adapted when actuated to rotate said shaft causing thereby the travel of said chains, said mechanism embodying a depending yoke, a motor driven sprocket chain independent of said shafts and mounted upon one of said supports, means carried by said motor driven sprocket chain and engaging said yoke for intermittently actuating said pawl and ratchet mechanism, and a hood inclosing said supports and having a sight opening.

5. An advertising device comprising an upper and a lower shaft, supports therefor, revolute heads carried by the shafts, traveling chains connecting the heads of one shaft to the heads of the other shaft, sign holding frames carried by said chains, said upper shaft having a projected end, a pawl and ratchet mechanism mounted upon said projected end of said shaft and adapted when actuated to rotate said shaft causing thereby the travel of said chains, said mechanism embodying a depending yoke, a motor driven sprocket chain independent of said shafts and mounted upon one of said supports, means carried by said motor driven sprocket chain and engaging said yoke for intermittently actuating said pawl and ratchet mechanism a hood inclosing said supports and having a sight opening, electrical lamps adjacent to said opening, circuit wire connections between said lamp and a source of

electrical energy, means carried by one of
said supports for controlling said circuit,
an intermittently operated trip device
mounted upon said projected end of said
5 shaft, and means carried by the motor driven
sprocket chain for operating said trip de-
vice causing thereby the actuation of said
controlling means.

In testimony whereof we affix our signa-
tures in the presence of two witnesses.

SAMUEL RICHARD.
FRED GLUCK.
